(57) **CLAIM**

The ornamental design for a tail light lens, as shown and described.

DESCRIPTION

FIG. 1 is a front, right side perspective view of the tail light lens;

FIG. 2 is a front left perspective view thereof;

FIG. 3 is a rear right perspective view thereof;

FIG. 4 is a rear left perspective view thereof;

FIG. 5 is a front view thereof;

FIG. 6 is a rear view thereof;

FIG. 7 is a right side view thereof;

FIG. 8 is a left side view thereof;

FIG. 9 is a top view thereof;

FIG. 10 is a bottom view thereof; and,

FIG. 11 is a front elevation view thereof, shown within an environment of use.

In FIG. 11, the broken lines depict boundaries and form no part of the claimed design. The depiction of a vehicle shown de-emphasized in half-tones represents environmental subject matter that forms no part of the claimed design.
